SEQUENTIAL PULSATION TIMER

Julius L. Solomon, Chicago, Ill., assignor to Welding Research, Inc., Chicago, Ill., a corporation of Illinois

Application June 15, 1953, Serial No. 361,608

11 Claims. (Cl. 235—132)

The invention relates to an electronic timing system for the individual timing of a number of operations or functions taking place in sequence such as may be performed by a welding machine and has reference more particularly to a timing circuit employing electronic elements including a cold cathode glow transfer tube in combination with control means therefor for effecting a counting function.

Objects of the invention are to provide an improved electronic system which will accurately time any desired operation by counting a predetermined number of electric pulses supplied by an electric current source; to provide an electronic timing system as described which may be utilized as a pulsation timer or as a heat-cool timer for seam welding; and to provide an electronic timer which will be simple in construction, embodying relatively few parts, and wherein the parts can be duplicated and connected in series relation for adding additional stages to the system.

A further object resides in the provision of a pulsation timer which will utilize two or more cold cathode glow transfer tubes as the counting elements, and wherein circuit control means are provided for switching from one counting element to the next at the end of their counting function.

A more specific object is to provide a pulsation timer which will incorporate a pair of counting elements as herein described in combination with a control circuit for switching the counting function from one element to the other so that they alternate in operation.

Another object resides in the provision of counting elements for a timing circuit and wherein said elements are electrically connected by a control circuit and by a commutating circuit, the latter circuit incorporating electric translating means for transmitting pulses and which are so connected to the elements that certain translating means will supply current pulses to be counted to one element and will supply current pulses for resetting purposes to another of the elements.

With these and various other objects in view, the invention may consist of certain novel features of construction and operation as will be more fully described and particularly pointed out in the specification, drawings and claims appended hereto.

In the drawings which illustrate an embodiment of the device and wherein like reference characters are used to designate like parts:

Figure 1 is a view illustrating schematically the various elements and circuit connections comprising the cold cathode glow transfer tube employed by the present invention as a counting instrumentality;

Figure 2 is a wiring diagram schematically illustrating the control circuit for switching the counting function from the counting instrumentality of one stage to the counting instrumentality of the next stage;

Figure 3 is a wiring diagram of the control circuit for a commercial form of pulsation timer coming within the invention;

2

Figure 3A is a view illustrating schematically the various elements and circuit connections for a pair of counting instrumentalities such as employed by the invention and which are electrically connected to the control circuit of Figure 3; and

Figure 4 is a wiring diagram schematically illustrating a modified form of timing system coming within the invention and wherein a series of cold cathode glow transfer tubes are employed for effecting functions in sequence.

Figure 1 of the drawings illustrates in diagrammatic form a cold cathode glow transfer tube which comprises the counting element for the present control circuit and to which is connected a source of direct current whereby the tube is energized. Other terminals of the tube connect with a sinusoidal pulse source, the pulses of which are counted by the tube during a counting function, and still other terminals of the tube are connected electrically to means whereby the tube can be reset each time for a predetermined count following an operation thereof. Said tube 10 is characterized by a single anode 11 and a plurality of cathodes 12, 13, 14, etc., ending with the last cathode 16. In a ten-cathode tube cathode 16 would therefore be the last or the tenth cathode, whereas, in a twelve-cathode tube said cathode 16 would be the last or twelfth cathode. It will be observed that the terminal C is electrically connected to cathode 16. In the construction of the tube the cathodes are arranged in a circle so that all will be relatively adjacent the common anode 11, and in order to transfer the glow from one cathode to the next in succession, the tube is provided with guides 18 and 20, the same being associated with each cathode. The conductors 21 and 22 connect the guides respectively to the guide terminals 23 and 24. Accordingly, a current pulse applied to terminal 23 will be supplied in turn to all of the guides 18 and in a similar manner a current pulse applied to terminal 24 will be supplied to all of the guides 20.

The anode 11 is connected through resistance 25 and 40 by a conductor 26 to the positive terminal 27 of a source of direct current, the voltage of which may be in the neighborhood of four hundred volts. The negative terminal of said direct current source has connection with conductor 28 leading to terminal D. The function of terminals C and D will be understood as the description 45 proceeds. Each cathode is electrically connected to conductor 28 by a resistance circuit which includes a switch, as clearly shown in Figure 1. For example, cathode 12 is connected by the resistance 30 and switch lever 31 to conductor 28, and in a similar manner cathode 13 is connected by resistance 32 and switch lever 33 to said conductor. With respect to the remaining cathodes, a circuit, including resistance and a switch lever, is provided, with 50 the exception of cathode 16, which is connected to conductor 28 by circuit 38, which includes resistance 39 only. The conductor 40, having connection with terminal G, is associated with conductor 28 and is connected by conductors 41, 42, 43 and 44 to switch terminals 45, 55 46, 47 and 48, respectively. It will be observed that the switch terminals 31, 33, 35 and 37, etc., have selective positions, in one of which they electrically connect with conductor 28 and in the other, they electrically connect with terminals 45, 46, etc., and with said conductor 40 60 leading to terminal G. The position of the switch elements for the various cathodes, whether connected to conductor 28 or conductor 40, will determine the particular cathode selected for starting a counting function. In the diagrammatic illustration of Figure 1 the second cathode, namely, 13, has its switch element 33 connected to terminal 46 so that this cathode has been 65 selected for starting the counting function and accord-

ingly in a ten-cathode tube the element will count eight current pulses for each operation thereof.

The terminal A is connected by means of conductors 50 and 52 to guide terminals 23 and 24, the connection including condensers 51 and 53. Both conductors 50 and 52 are connected to a parallel circuit which includes resistances 54 and 55. Said parallel circuit at a midpoint between the resistances is connected by conductor 56 to a potentiometer including the divider 57 and resistance 58, the latter being connected across the direct current source previously described. It will be noted that pointer 57 is positioned at point 0 on the resistance 58 and thus the guides 18 and 20 are normally maintained at a slightly higher potential than that applied to the cathodes. The resistance 53 is connected at 60 to conductor 23 and the terminal B also has connection with said conductor 23 through the conductor 61.

In the event terminals A and B are connected to a source of alternating current of sinusoidal wave form it will be understood that condensers 51 and 53 in combination with the connecting circuit, including the resistances 54 and 55, function as a phase shift circuit to shift the phase of the voltages applied to the guide terminals 23 and 24. For example, it is possible to apply to guide terminal 23 a leading voltage and to a guide terminal 24 a lagging voltage so that the current impulse is first indicated at guides 18 by a drop in the potential of said guides and after a time interval, depending on the characteristics of the phase shift circuit, the current pulse is indicated at guides 20 by a similar drop in potential.

The counting element of Figure 1 is activated by the application of periodic impulses to terminals D and G. Since switch element 33 of cathode 13 is the only element connecting with terminal G the said periodic current impulses produce a glow between anode 11 and cathode 13. To initiate a counting function current pulses are applied to terminals A and E, the same having a uniform time interval such as may be produced by an alternating current of sinusoidal wave form. The application of the first pulse to terminals A and B will energize the guides 18 and the glow is accordingly transferred from cathode 13 to the guide 18 associated therewith. Immediately thereafter the guide 20, associated with cathode 13 is energized and the glow is transferred from guide 18 to guide 20. Upon decay of the voltage applied to guide 20 the glow is transferred to cathode 14, since as explained, the guides are normally maintained at a potential slightly above that of the cathodes. The next impulse applied to points A and B will cause transfer of the glow from cathode 14 to guide 18 associated therewith, then to its guide 20, and then to 15 the next cathode in succession. Accordingly, for each impulse the glow is transferred from one cathode to the next and a counting function accordingly takes place. At the count of the eighth impulse the glow will have been transferred to cathode 16 representing the last cathode of the counting element. Immediately upon cathode 16 conducting the glow, current flow takes place through resistance 39 of conductor 38 and the drop in voltage across this resistance is exhibited at the terminals C and D. In accordance with the invention the voltage thus appearing across terminals C and D is used to transfer the counting operation to a second counting element which may represent the second stage in a sequencing series.

Figure 2 of the drawings is a wiring diagram illustrating in schematic form a control circuit for a two-stage counting system wherein each stage employs a counting element such as shown in Figure 1, having terminals A and B, C and D, and D and G. The main function of the control circuit is to alternately render conductive a pair of electric discharge valves such as thyratrons whereby the counting function is shifted from one counting element to the next and so on, with the operation being repeated as long as the control circuit remains energized.

More specifically, the control circuit of Figure 2 is dis-

closed in connection with two counting elements which are generally designated by numerals 70 and 80, each element being constructed as explained in connection with Figure 1 and having operation to perform a counting of a predetermined number of electrical impulses such as may be applied to the terminals A and B of the elements. The thyratrons of Figure 2 are indicated by numerals 71 and 81 and an electric discharge valve of the double triode type is indicated by numerals 72 and 82. The resistances 73 and 83 have electrical connection with the anodes of valves 71 and 81. The anodes of the double triode valve 72, 82 are respectively connected to primary windings 74 and 84 of the transformers 75 and 85, each transformer having a pair of secondary windings 76 and 86 and 77 for transformer 75 and 86 and 87 for transformer 85.

The control circuit is energized by a source of direct current connected across conductors 90 and 91 with the positive terminal of the source connecting with conductor 90. The resistance 92 connects at its respective ends with conductors 90 and 91 and is accordingly in parallel relation with the direct current source, the said resistance and the pointer 93 providing a potentiometer which may be adjusted to vary the potential applied to the pair of thyratrons 71 and 81. The conductor 94 connects with the pointer 93 and the resistances 73 and 83 in turn have connection with said conductor 94 and with the anode 95 of valve 71 and anode 96 of valve 81. The cathodes 97 and 98 of said valves are joined by conductor 99 which is in turn connected to conductor 91 through resistance 100 and the condenser 101 in parallel circuit relation with the resistance. The control grid 78 of valve 71 is connected by conductor 102 to the terminal C of the counting element 70, whereas the control grid 88 of valve 81 is connected by conductor 103 to terminal C of the counting element 80. Conductor 90, having connection with the positive terminal of the direct current source, leads to the cathodes 104 and 105 of the valve 72, 82. The anodes 106 and 107 thereof connect with the primary windings 74 and 84. The control grid 103 of triode 72 is connected by conductor 109 to resistance 83, whereas control grid 110 of triode 82 is connected by conductor 111 to resistance 73. Accordingly, the conductivity of triode 72 is controlled by that of thyratron 71, whereas the conductivity of triode 82 is controlled by that of thyratron 81.

The primary windings 74 and 84 of the transformers 75 and 85 connect with one terminal of secondary winding 112 of transformer 113. Said transformer 113 is provided with primary winding 114, the terminals of which are suitably connected to a source of sixty cycle alternating current of approximately one hundred and ten volts. The opposite terminal of secondary winding 112 is connected by conductor 115 to the cathodes 104 and 105 of the triodes 72 and 82. As previously explained, the primary windings 74 and 84 each have associated therewith a pair of secondary windings, as clearly shown in Figure 2. Secondary winding 76 is connected by conductors 116 and 117 to terminals D, G, respectively of the counting element 70. In a similar manner secondary winding 86 is connected by conductors 118 and 119 to the terminals D, G, respectively of counting element 80. Secondary winding 77 is connected through conductors 120 and 121 to terminals A, B of the counting element 70. Secondary winding 87 is connected by the conductors 122 and 123 to the terminals A, B of the counting element 80. Conductor 124 connects conductor 91 with terminal D of counting element 70, whereas conductor 125 in a similar manner connects conductor 91 to terminal D of counting element 80. A bypass circuit is provided in connection with conductors 116 and 117, the same including the direct current battery 126 and switch 127. Conductor 117 and thus terminal G of counting element 70 can be connected to the positive end of the battery 126 through switch 127. The negative end of the battery has connection with conductor 116. Conductor 122, leading to terminal A of the

counting element 70, is provided with a main switch 128 which controls the operation of the control circuit and the starting of the counting functions of the elements 70 and 80. It will be observed that the main switch 128 has a fixed relation through member 130 with switch 127 so that when one switch is closed the other is positively held open.

For explaining the operation of the control circuit of Figure 2 it will be assumed that switch 128 is closed and that thyratron 71 is conducting. Accordingly, a voltage will exist across resistance 100 in the cathode circuit common to both thyratrons so that a negative bias is maintained on the screen grid of thyratron 81. If a positive pulse is supplied by terminals C, D of counting element 80 the thyratron 81 will become conductive and 71 will be rendered nonconductive. This switching from one tube to the other is effected by the capacitor 131. While tube 71 was conducting capacitor 131 was charged in a manner whereby the end of the capacitor which is connected to the anode of tube 71 is negative and that end which is connected to the anode of 81 is positive. When 81 is rendered conductive by the positive pulse applied to grid 83, the positive end of capacitor 131 is electrically connected with the cathode of 71 so that the anode 95 of said tube is thus made negative with respect to its cathode which extinguishes said tube.

With thyratron 81 conducting, it will be seen that a voltage drop will appear across resistance 83 between the slider in contact therewith and the positive end of said resistance. This voltage is applied to the grid 108 of the triode 72. In the same grid circuit there is also a voltage appearing across the resistance 92 from the positive end to the slider 93. Between grid 108 and cathode 104 of the triode 72 there is thus the sum of said two voltages, one appearing across part of resistance 92 and the other across part of resistance 83. The voltage across part of 92 is sufficiently low to allow the triodes to conduct. However, the addition of the voltage across part of resistance 83 brings the grid 108 to the cutoff region and stops conduction of 72. Accordingly, with thyratron 81 conducting, triode 72 will be held nonconductive, whereas, triode 82 will be conducting since there is no voltage appearing across the resistance 73. Transformer 85 will therefore be passing current and an alternating voltage will be induced in its secondary windings 86 and 87. The current pulses generated in the secondary winding 86 are applied to terminals D, G of the counting element 80 and a periodic glow is thus maintained in said counting element from anode to the particular cathode which has been selected for starting the counting function, all depending on the particular count desired of this element. The current pulses generated in secondary winding 87 will be applied to terminals A and B of counting element 70 and said element is thus operative to effect a counting function. The number of pulses to be counted by element 70 will, of course, depend on the cathode selected for starting the count. When the glow has been transferred to the last cathode of the counting element 70 the voltage caused to appear across terminals C, D thereof will apply a positive pulse to thyratron 71, causing it to become conductive. The same action involving the capacitor 131 takes place as before and thyratron 81 is immediately extinguished. With tube 71 conducting, a voltage drop now appears across 73 and there is no voltage across 83. This switch in the conductivity of the thyratrons effects a switch in the conductivity of the triodes so that 82 is extinguished and triode 72 is rendered conductive. Transformer 75 accordingly passes current and pulses are induced in its secondary windings. The current pulses induced in winding 76 are applied to terminals D, G of counting element 70 to reset this element in a manner as previously explained. The current pulses induced in winding 77 are applied to terminals A and B of counting element 80 and this element now be-

comes operative to effect a counting function wherein each pulse applied to terminals A and B will be counted by a transfer of the glow from the starting cathode to the last cathode, whereupon a signal voltage is produced across its terminals C, D. As previously explained, this signal voltage applies a positive pulse to the grid 88 and thyratron 81 is again rendered conductive, thus completing the cycle of operations.

The counting functions will alternate between elements 10 70 and 80 and as long as the initiating switch 128 is maintained in closed position. If the switch is thrown to "off" position while counter 80 is in operation the counting by this element will continue to the end of the count, after which the control circuit will become 15 inoperative. Thus the heat time is never cut short. However, should switch 128 be opened during the operation of counting element 70 for the cool time, the counting function will stop immediately since the pulses to terminals A and B are discontinued. With the opening of 128 switch 127 is automatically closed and counting element 70 is accordingly reset by the current supplied by battery 116.

The timing system of Figure 2 will operate in a manner to give accurate timing functions and such a system will 25 find extensive utility as a pulsation timer or as a heat-cool timer for seam welding. The counting element 80 would function to time the duration of the welding heat and timing element 70 would operate to time the duration of the cooling periods between welds. For a sequencing timer for timing three or more operations taking place in sequence the system could be amplified by adding additional stages, each stage incorporating a counting element having the characteristics and mode of operation as described.

35 Referring again to Figure 1, a modification is disclosed for resetting the counting element at the end of each counting function. The terminals E, F are substituted for terminals D, G. Said terminals have connection respectively with conductors 132 and 133 which are connected by the current limiting resistor 134. Conductor 132 leads to the grid 135 of the electric discharge tube 136. The anode 137 of said tube is connected to conductor 40 and through current limiting resistor 138 connection is made with conductor 28. The cathode 140 is joined by conductor 141 to the positive end 142 of the battery 143, the negative end of which connects with conductor 133. A second battery is employed, namely, 45 144, the same being joined by conductor 145 to terminal 142 and by conductor 146 to conductor 28.

50 When the resetting pulses are applied to terminals E and F in the manner as described with respect to terminals D, G, it will be understood that tube 138 will be rendered conductive and will thus transmit amplified current pulses to maintain the glow between the anode 11 and the particular cathode selected for initiating the counting function. When the pulses to terminals E and F are terminated the tube 138 is held in a nonconductive state since grid 135 is maintained at a potential which is more negative than its cathode 140.

55 Figures 3 and 3A are wiring diagrams schematically disclosing a commercial form of counting system wherein in a pair of the counting elements of Figure 1 are alternately controlled as regards their counting function by means of a control circuit. Figure 3 is analogous in all respects to the control circuit shown in Figure 2 and similar elements are identified by related reference numerals. The thyratrons are numbered 271 and 281 and the resistors connecting with the respective anodes of the thyratrons are identified by 273 and 283. Thus, as previously explained, the conductivity of the thyratrons controls the conductivity of the triodes 272 and 282. The transformer 275 is associated with triode 272 and transformer 285 is associated with triode 282. Each 70 transformer has a pair of secondary windings which are 75

connected by suitable conductors to certain terminals of the counting elements 270 and 280 shown in Figure 3A.

As a result of the showing made by Figures 3 and 3A it is possible to obtain an understanding of the manner in which the electronic parts within the counting elements 270 and 280 are electrically connected to the secondary windings of the transformers which comprise the impulse generating devices of the control circuit. Considering first winding 277, it will be observed that the same is connected by conductors 320 and 321 to terminals A and B of the counting element 280. In a similar manner winding 287 is connected by conductors 322 and 323 to terminals A and B of the counting element 270. Also by tracing the circuits for the windings 276 and 286 it will be seen that these are electrically connected to terminals D and G, there being provided in this modification a double diode 329 interposed in the circuits for the windings respectively. Also the switch 328 has a fixed relation with switch 327 through member 330 so that when one is open the other is closed. With the opening of switch 328, if counting element 280 is in operation, it will continue until the end of the counting function and thus the heat time is never cut short. However, if counting element 270 for the cool time is in operation when switch 328 is opened, its counting function is ended immediately. Switch 327 is simultaneously closed and the current source 316 is rendered operative for resetting the counting element.

Referring to the modification shown in Figure 4, it will be observed that four counting elements are employed, the same being identified by numerals 410, 411, 412 and 413, and accordingly this modification of the invention provides a sequence timer wherein each event in the series is individually timed by its respective counting element. Each element consists of a cold cathode glow transfer tube embodying the same circuit elements and circuit connections as illustrated in connection with the tube of Figure 1. Each counting element is therefore provided with terminals A, B; C, D; and D, G. The said terminals A, B are connected with suitable means for supplying current pulses to the elements to be counted thereby. A signal voltage is produced across terminal C, D to signify the end of the counting operation of its respective element and the terminals D, G connect with the resetting means of each counting element so that the element can be reset by a resetting pulse applied across said terminals.

The counting elements are electrically connected by an improved control circuit essentially consisting of the cold cathode gas tubes 414, 415, 416 and 417 and the cathode resistors 418, 419, 420 and 421, respectively. Each of the cold cathode gas tubes consists of an anode, a cathode, and a control grid. With respect to tube 414, it will be seen that the anode 422 is connected to the conductor 423, comprising the positive terminal of the direct current source, which is provided for energizing the said gas tubes. The conductor 424 constitutes the negative terminal of said power source, and the cathode 425 of the tube 414 has electrical connection through the cathode resistor 418 with said negative conductor 424, said conductor being additionally connected through 426 to terminal D of the counter 410. Terminal C of said counter is connected through conductor 427, condenser 428, and switch 430 with the grid 431 of tube 414.

The counting element 411 is similarly connected through its terminals C, D to cold cathode gas tube 415, the anode 432 thereof having connection to the positive conductor 423, the cathode 433 thereof connecting through resistor 419 with negative conductor 424 and the grid 434 having connection through conductor 435 to terminal C. The terminal D is connected through conductor 436 to 424. Similar elements electrically connect the terminals C and D of counting element 412 with tube 416 and likewise counting element 413 is connected with tube 417. With respect to this last tube,

attention is directed to switch 447 which is interposed in the positive conductor 423 at a point beyond the connection thereto of the anode 442 of said tube. Accordingly, it will be seen that the anode is at all times connected to said positive terminal so as to energize tube 417.

The invention provides means for switching the conductivity from one cold cathode tube to the next. For example, should tube 414 be conducting and should tube 415 be rendered conductive, then tube 414 is immediately snuffed out by the capacitance having electrical connection with the cathode circuits of the tubes. The conductor 448 electrically connects the four cathodes of the tubes respectively and in between each tube there is interposed a condenser 450, the operation of which is such that only one tube may be conductive at a time. Such operation will be presently described in detail.

The transformers 451, 452, 453 and 454, in combination with the vacuum tubes 455 to 458, respectively, constitute a pulse-sending or commutating network for the purpose of transmitting current pulses to be counted by the counting elements and for additionally transmitting reset pulses to said elements. The vacuum tubes are connected in parallel across conductors 460 and 461, the said conductors constituting the terminals of the secondary winding 462 of the power transformer 463 having primary winding 464. The terminals of winding 464 are connected to any suitable source of alternating current identified by leads L₁ and L₂. With respect to vacuum tube 455, it will be seen that its anode 465 thereof is connected to primary winding 466 of transformer 451, which winding is in turn connected to conductor 460. The cathode 467 of said tube 455 is connected to conductor 461, whereas the grid 468 thereof has electrical connection through conductor 470 to cathode 443 of the gas tube 417, said connection being made between the cathode and resistor 421 and said tube. In a similar manner the vacuum tube 456 is connected across the conductors 460 and 461, with the grid 474 being electrically connected by conductor 475 to the cathode 425 of tube 414 at a point between the tube and the cathode resistor 418. Similar connections are provided for vacuum tubes 457 and 458, it being seen that the grid 479 of tube 457 is connected by conductor 480 to cathode 433 of the gas tube 415, whereas vacuum tube 458 has its grid 484 connected through conductor 485 to cathode 438 of the gas tube 416. A source of biasing potential in the form of a direct current battery 486 has its positive terminal connected to conductor 461 with its negative terminal being electrically connected through conductor 487 to the negative conductor 424.

Referring more particularly to transformer 451, it will be understood that this transformer is provided with a plurality of secondary windings. One winding 490 is connected through conductors 489 with terminal A, B of element 410. The other secondary windings 490 thereof have connection with the reset terminals D, G of counting element 411, 412 and 413, respectively. Transformer 452 has two secondary windings, one winding identified by numeral 491 having electrical connection with the reset terminals of counting element 410, with the other secondary winding, namely, 492, of said transformer having electrical connection with terminals A, B of counting element 411. Transformer 453 is provided with one secondary winding, namely, 493, which has electrical connection with terminals A, B of counting element 412 and in a similar manner transformer 454 has one secondary winding, namely, 494, which electrically connects with terminals A, B of counting element 413.

With switch 447 in the position as shown, the gas tube 417 is rendered conductive and the same will pass current from the positive terminal to the negative terminal of the direct current power source. Current flow as permitted by the conductivity of this gas tube will produce a voltage across the cathode resistor 421. From

an examination of the cathode to grid circuit of vacuum tube 455, it will be seen that battery 436 supplies a negative bias to the grid 423 thereof through resistor 421 and conductor 470. This same bias is supplied to the grid of vacuum tube 456, 457 and 458 through the cathode resistors 418, 419 and 420, and respective grid conductors. These tubes are therefore normally maintained in a nonconductive state by this negative biasing voltage. With the gas tube 417 conducting, the voltage across resistor 421 is sufficient to bring the grid of vacuum tube 455 to a positive potential with respect to its cathode and the vacuum tube accordingly conducts to pass alternating current pulses from the power supply L_1, L_2 through the primary winding 466 of transformer 451. One secondary winding, namely, 483, of this transformer is connected to terminals A, B of counter 410 and said counter accordingly begins a counting operation to count the pulses thus supplied thereto by transferring the glow from cathode to cathode of said counter, all as explained in connection with Figure 1. When the glow has been transferred to the last or tenth cathode a voltage pulse is applied to terminals C, D of said counting element 410 and the counting operation is repeated. However, inasmuch as switch 430 is open the voltage pulse is not supplied to gas tube 414. The additional secondary windings 490 of transformer 451 have connection with the reset terminals of counters 411, 412 and 413, respectively, and the voltage pulses generated in these secondary windings serve to reset the three counters to a preset position.

When switch 427 is moved into an upward position to connect conductor 423 to the positive terminal of the direct current supply source and with switch 430 being closed, it will be seen that the voltage pulse applied across terminals C, D of counting element 410 will eventually be supplied to grid 431 of gas tube 414, rendering this gas tube conductive. By reason of the capacitance 459 having electrical connection with the cathodes of the gas tubes, the tube 417 is extinguished. This is due to the fact that with both tubes, namely, 417 and 414, conducting, the action of the capacitance is to render the cathode of tube 417 positive with respect to its anode, which results in stopping the conduction of this gas tube. The grid 468 of vacuum tube 455 will return to its negative biasing potential to stop conduction of said tube and simultaneously tube 456 will conduct inasmuch as the grid thereof is brought to a conducting potential by the voltage drop across cathode resistor 418. Counting element 411 is now rendered operative since current pulses to be counted are supplied thereto through secondary winding 492 of transformer 452. As the glow is transferred from the cathodes of counting element 411 from its preset position to its last or tenth cathode, a pulse will eventually be generated, which is supplied through conductor 435 to the grid of gas tube 415. This voltage pulse starts conduction of tube 415 and simultaneously extinguishes conduction of tube 414. With tube 415 now conductive the grid 479 of vacuum tube 457 is brought to a conductive potential so that this vacuum tube fires and current pulses to be counted are now supplied to counting element 412 through secondary winding 493 of transformer 453. Eventually this counting element will reach the end of its counting operation to supply a voltage pulse to the grid of gas tube 416. Conductivity of this gas tube will cause vacuum tube 458 to conduct and as a result current pulses to be counted are supplied to counting element 413 through secondary winding 494 of transformer 454. When the glow is transferred to the tenth cathode of element 413 the end of its counting function is indicated by the single voltage supplied to the grid of gas tube 417 and once again this tube is rendered conductive to effect conduction of vacuum tube 455. The counting procedure above described will continue from one counting element to the next in sequence as long as switch 430 remains closed. Should this switch 430 be opened dur-

ing any part of the operation, the counting sequence will continue until vacuum tube 455 is again rendered conductive. With switch 430 being open the control circuit is rendered inoperative so that the sequencing, as regards the counters, is terminated. However, the circuit remains ready for operation at all times and it is only necessary to close switch 430 to start the counting function with counting element 410 and continuing in sequence through the other counters.

10 The timing system of Figure 4 is characterized by a series of cold cathode glow transfer tubes which constitute counting elements and which are electrically connected to a control circuit for switching from one counting element to the next as each element completes its counting function. The circuit elements for the timing system are completed by a pulse transmitting or commutating circuit which is electrically associated with the control circuit. In operation the counting elements 411, 412 and 413 may control the squeeze time, the weld time, and the hold time, respectively, of a welding operation, for example, with the counting element 410 controlling the off time. The timing system is so constructed and arranged that an accurate count is secured for each counting operation of the elements 411, 412 and 413 and if the said operations are repeated the counting element 410 will produce a full count for the offtime period, all as determined by the presetting of the elements. Also, it will be understood that upon opening of switch 430 the timing system will continue in operation until gas tube 30 417 is rendered conductive, which energizes vacuum tube 455, controlling the offtime counting element 410. For timing more than four operations, it is only necessary to add additional stages to the system as shown in Figure 4, with each stage incorporating a counting element, a gas tube and a vacuum tube, all having the circuit connections and mode of operation as described.

40 The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

45 1. In a pulsation timer, the combination with a first counting element, a second counting element, and an electric source providing periodic current pulses to be counted by the elements, of a control circuit for rendering the counting elements alternately operative for performing a counting function, said control circuit providing first and second electric translating means having connection with the electric source for transmitting the periodic current pulses to the elements, the first translating means transmitting to the second element current pulses to be counted thereby and transmitting to the first element current pulses for resetting the element, the second translating means transmitting to the first element current pulses to be counted thereby and transmitting to the second element current pulses for resetting the element, an electric discharge device for each electric translating means for controlling by its conductivity the energization of its particular translating means, said discharge devices being electrically connected in a manner whereby only one is conductive at a time, and means electrically connecting the counting elements with the discharge devices in a selective manner, whereby each element at the completion of its counting function supplies a signal voltage to a certain one of the discharge devices to effect alternate conductivity of the discharge devices.

50 2. In a pulsation timer, the combination with a first counting element for counting electric current pulses, a second counting element identical in construction and operation to the first, and an alternating current source providing periodic current pulses to be counted by said elements, of a control circuit for rendering the counting elements alternately operative for performing a counting

function, said control circuit providing first and second transformers each including a pair of secondary windings inductively connecting with the electric source for supplying the periodic current pulses to the elements, the first transformer supplying to the second element current pulses to be counted thereby and supplying to the first element current pulses for resetting the element, the second transformer supplying to the first element current pulses to be counted thereby and supplying to the second element current pulses for resetting the element, an electric discharge device for each transformer for controlling by its conductivity current flow through its particular transformer, circuit means electrically connecting said discharge devices in a manner whereby only one is conductive at a time, and other circuit means electrically connecting the counting elements with the discharge devices in a selective manner whereby each element at the completion of its counting function supplies a signal voltage to a certain one of the discharge devices to effect alternate conductivity of the discharge devices.

3. In a pulsation timer, the combination with a first counting element for counting electric current pulses, a second counting element identical in construction and operation to the first, and an alternating current source providing periodic current pulses to be counted by said elements, of a control circuit for rendering the counting elements alternately operative for performing a counting function, said control circuit providing first and second transformers each including a pair of secondary windings inductively connecting with the electric source for supplying the periodic current pulses to the elements, the first transformer supplying to the second element current pulses to be counted thereby and supplying to the first element current pulses for resetting the element, the second transformer supplying to the first element current pulses to be counted thereby and supplying to the second element current pulses for resetting the element, an electric discharge device for each transformer for controlling by its conductivity current flow through its particular transformer, each electric discharge device including an anode, a cathode, and a control grid, circuit means connecting said discharge devices in a manner whereby the conductivity of one is terminated upon the other being rendered conductive, and other circuit means electrically connecting each counting element to the control grid of a certain electric discharge device, whereby each element at the completion of its counting function supplies a signal voltage to the grid of the discharge device connected thereto to effect alternate conductivity of the discharge devices.

4. Apparatus for counting electric current pulses by means of counting elements of the type employing an anode and a plurality of cathodes with guide terminals located between the cathodes, whereby the electric pulses energize the cathodes in succession and can therefore be counted, of a control circuit provided by said apparatus for controlling the counting function of said elements, said control circuit including an electric discharge device for each counting element to be controlled by said circuit, circuit means electrically connecting the discharge devices in a manner whereby only one can be conductive at a time, a translating device for each counting element, at least one of said translating devices when energized transmitting to one counting element current pulses to be counted thereby and transmitting to another of said counting elements current pulses for resetting purposes, electrical connections between the discharge devices and the translating devices respectively for individually energizing the translating devices as the discharge devices are individually rendered conductive, and means electrically connecting the counting elements with the discharge devices in a selective manner, whereby each element at the completion of its counting function supplies a signal voltage to a certain one of the discharge devices to effect conductivity thereof.

5. Apparatus for counting electric current pulses by

means of counting elements of the type employing an anode and a plurality of cathodes with guide terminals located between the cathodes, whereby the electric pulses energize the cathodes in succession and can therefore be counted, of a control circuit provided by the apparatus for controlling the counting function of said elements, said control circuit including an electric discharge device for each element included in the control circuit, each discharge device having an anode, a cathode and a control grid, circuit means including capacitance electrically connecting the discharge devices in a manner whereby upon any one device being rendered conductive the others are caused to become non-conductive, a transformer for each counting element, each transformer supplying to one counting element current pulses to be counted thereby and supplying to another of said counting elements current pulses for resetting the element, electrical connections between the discharge devices and the transformers respectively, whereby each discharge device by its conductivity controls current flow through its particular transformer, and a conductor connecting each counting element with the grid of a certain discharge device, whereby each element at the completion of its counting function supplies a signal voltage to one of the discharge devices for effecting conductivity thereof.

6. For use as a pulsation timer, apparatus for counting electric current pulses by means of electronic counting elements of the type employing an anode and a plurality of cathodes with guide terminals located between the cathodes, whereby the electric pulses energize the cathodes in succession and can therefore be counted, of a control circuit provided by the apparatus for controlling the counting function of the elements, said control circuit providing a plurality of translating means equal in number to the counting elements and adapted to have connection with an electric current source producing periodic current pulses, at least one of said translating means supplying to the guide terminals of one counting element current pulses to be counted thereby and supplying to the resetting terminals of another of said elements current pulses for resetting purposes, an electric discharge device for each translating means and having connection therewith for controlling by its conductivity the energization of its particular translating means, each discharge device including an anode, a cathode and a control grid, and circuit means electrically connecting each counting element with the control grid of a certain discharge device, whereby each element at the completion of its counting function supplies a signal voltage to the grid of the discharge device connected thereto to effect conductivity of said discharge device.

7. For use as a pulsation timer, apparatus for counting electric current pulses as defined by claim 6, wherein each translating means includes a transformer having a primary winding connected to the electric current source and having two secondary windings, one secondary winding thereof supplying to the guide terminals of said one counting element the current pulses to be counted thereby and the other secondary winding supplying to the said resetting terminals of another of said elements the current pulses for resetting purposes, wherein the circuit means electrically connects the last cathode of each counting element with the control grid of a certain discharge device, and additionally including resistance in the circuit of the last cathode of each element, whereby the signal voltage produced by each counting element at the end of its counting function is caused by the voltage drop across the said resistance as a result of current flow taking place upon energization of the last cathode thereof.

8. For use as a pulsation timer, apparatus for counting electric current pulses by means of electric counting elements of the type employing an anode and a plurality of cathodes with guide terminals located between the cathodes, whereby the electric pulses energize the cathodes in succession and can therefore be counted, said counting elements each having input terminals, output

terminals and resetting terminals, of a control circuit electrically connecting the elements in tandem relation and which controls the operation of the elements in sequence, said circuit including a source of electrical energy, an electric discharge valve for each counting element connected across said source, circuit means connecting the output terminals of each counting element with the grid and cathode of its respective discharge valve, whereby the signal voltage produced by each element at the termination of a counting operation thereof is caused to render its discharge valve conductive, a commutating circuit including an electric discharge valve for each valve of the control circuit, means in electrical connection with the first valve of the commutating circuit for supplying the input terminals of the first counting element with electric pulses to be counted thereby and for supplying to the reset terminals of the remaining counting elements electric pulses for resetting purposes, and other means in electrical connection with each remaining valve of the commutating circuit for respectively supplying to the input terminals of the remaining counting elements electric pulses to be counted thereby.

9. For use as a pulsation timer, apparatus for counting electric current pulses by means of electronic counting elements of the type employing an anode and a plurality of cathodes with guide terminals located between the cathodes, whereby the electric pulses energize the cathodes in succession and can therefore be counted, said counting elements each having input terminals connecting with the guide terminals of the element, output terminals across which there is produced a signal voltage at the completion of the counting operation thereof, and resetting terminals to which there is supplied a current pulse for resetting purposes, of a control circuit electrically connecting the elements in tandem relation and which controls the operation of the elements in sequence, said circuit including a source of direct current, a normally non-conductive electrical discharge valve for each counting element connected across said source, circuit means connecting the output terminals of each counting element with the grid and cathode of its respective discharge valve, whereby the signal voltage produced by each counting element at the end of its counting operation will render its discharge valve conductive, a commutating circuit including a normally non-conductive electric discharge valve for each valve of the control circuit, a transformer having electrical connection with the first valve of the commutating circuit for supplying to the input terminals of the first counting element electric pulses to be counted thereby and for supplying to the resetting terminals of the remaining counting elements electric pulses for resetting purposes, and a second transformer for each remaining valve of the commutating circuit and in electrical connection therewith for respectively supplying to the input terminals of the remaining counting elements electric pulses to be counted thereby.

10. For use as a pulsation timer, apparatus for count-

ing electric current pulses by means of electronic counting elements of the type employing an anode and a plurality of cathodes with guide terminals located between the cathodes, whereby the electric pulses energize the cathodes in succession and can therefore be counted, said counting elements each having input terminals connecting with the guide terminals and to which are supplied electric pulses to be counted, said counting elements each having output terminals across which there is produced a signal voltage at the completion of the counting operation thereof, and said elements each having resetting terminals to which there is supplied a current pulse for resetting purposes, of a control circuit electrically connecting the elements in tandem relation and which controls the operation of the elements in sequence, said circuit including a source of electric energy, a normally non-conductive electric discharge valve for each counting element connected across said source, circuit means connecting the output terminals of each counting element with the grid and cathode of its respective discharge valve, whereby the signal voltage produced by each counting element will render its discharge valve conductive, a capacitor located between and in electrical connection with adjacent discharge valves for rendering the succeeding valve non-conductive upon the preceding valve becoming conductive, a commutating circuit including a normally non-conductive electric discharge valve for each valve of the control circuit, means in electrical connection with the first valve of the commutating circuit and operative upon conductivity of said first valve for supplying to the input terminals of the first counting element electric pulses to be counted and for supplying to the resetting terminals of the remaining counting elements electric pulses for resetting purposes, and other means in electrical connection with each remaining valve of the commutating circuit and operative upon conductivity of its valve for respectively supplying to the input terminals of the remaining counting elements electric pulses to be counted thereby.

11. Apparatus for counting electric current pulses by means of electric counting elements as defined by claim 10, additionally including conductors respectively connecting the cathodes of certain valves of the control circuit with the grid of certain valves of the commutating circuit, whereby the latter valves are rendered conductive upon their connected valve in the control circuit becoming conductive.
